UNITED STATES PATENT OFFICE.

BERNARD T. STEBER, OF UTICA, NEW YORK.

KNITTED FABRIC.

No. 920,207.

Specification of Letters Patent.

Patented May 4, 1909.

Application filed September 28, 1907. Serial No. 394,970.

To all whom it may concern:

Be it known that I, BERNARD T. STEBER, a citizen of the United States, residing at Utica, in the county of Oneida, State of New York, have invented an Improvement in Knitted Fabrics, of which the following description, in connection with the accompanying drawings, is a specification, like letters on the drawings representing like parts.

10 This invention relates to knitted fabrics, and it has for its purpose, in the specific embodiment of the invention here presented, the production of a fabric that is sufficiently open to afford a free passage of air, and thus 15 be well adapted for summer use, and yet one which at the same time is sufficiently absorbent to meet the needs of such use.

In order that the principles of the invention may be readily understood, I have disclosed certain forms or embodiments thereof in the accompanying drawings, it being understood, however, that my invention is in no wise restricted to the types herein indicated.

25 Referring to the drawings—Figure 1 represents the back side of a fabric embodying my invention; and Figs. 2, 3, 4, 5 and 6 are similar views of other forms of fabric likewise embodying my invention.

30 In each of the forms of my invention herein illustrated, I have represented the fabric as one that may be knitted upon that type of machine disclosed in my Patent No. 810,578, Jan. 23, 1906, it being understood that in 35 knitting the present fabric, I remove from the machine or render inoperative the yarn engaging hooks 16, since the purpose of the present invention is not to provide a knitted fabric having a fleecing face but one particu- 40 larly adapted for summer wear.

While my invention is particularly applicable to that type of fabric that may be knitted upon the machine shown in my said patent, which fabric may, except as herein- 45 after described, be similar to that shown in Fig. 2 of my Patent No. 865,279, Sept. 3, 1907, yet I may embody my invention in other types of fabrics than that referred to. I find, however, that the type of fabric dis- 50 closed in Fig. 2 of the said Patent No. 865,279 is well adapted for summer wear, owing to the open or mesh like character thereof. A fabric knitted as illustrated in Fig. 2 of my said Patent No. 865,279 and formed through- 55 out of a fine, single ply soft, spun yarn, such, for example, as No. 40 cotton yarn, would present

an ideal structure so far as lightness and the open or mesh like character thereof is concerned, but not only is such a yarn very tender, so that in the knitting of the garment 60 frequent breakages of the yarn occur and in use the yarns of the garment are liable quickly to rupture, but the absorptive properties, which are highly necessary in a garment for summer use, exist only to a minimum extent in a fabric constructed throughout 65 of such a yarn.

In order to meet the exigency above stated, I introduce into the fabric at suitable points a heavier yarn having greater absorptive 70 properties. Considering that form of my invention wherein the fabric is knitted upon a circular machine, a fabric having such yarn or yarns introduced will present relatively heavier annular ridges between which 75 exist the clearly defined diamond-shaped meshes characteristic of that type of fabric shown in Fig. 2 of my said Patent No. 865,279, when such type of fabric is employed. In the use of ordinary cotton yarn, 80

however, I have discovered in the course of my experiments that it is substantially impossible, without very frequent breakage, to introduce a yarn heavy enough to have a full absorptive value desired into a fabric other- 85 wise composed of a fine or tender yarn, this being true whether or not the fabric be of the particular type shown in Fig. 2 of my said patent. That is to say, I cannot for the reasons given satisfactorily form a garment 90 of ordinary yarn, in which the predominating yarn is, for example, a tender yarn, such as No. 40 cotton yarn, and the absorptive yarn is No. 10 cotton yarn by interknitting one of said yarns directly into the other. This will 95

be appreciated when it is understood that if a course or courses of loops be formed upon a fine, tender yarn, such as No. 40 cotton yarn, the introduction of loops of a heavy 100 yarn directly into the loops of such tender yarn subject the latter to such strain as to rupture the same. Then again, in introducing such loops of heavy yarn it is necessary to crowd through each loop of tender yarn the needle and the heavy absorptive yarn. 105 This is apt so to distend the loops of tender yarn as to break the same. Notwithstanding this difficulty and in order to meet the demand for a light summer garment of open character having heavy absorptive yarn incorporated therein, I have, after much experimenting and in the preferred embodi- 110

ment of my invention, introduced yarns of graduated sizes, as will be more specifically described in connection with the drawings.

Referring to Fig. 1, I have therein represented a fabric knitted from a plurality of threads, each thread or series of threads forming independent wales alternately arranged. This may be done by arranging the needles of the machine in the manner 10 fully disclosed in my Patent No. 810,578, wherein the needles are arranged in two groups, one group comprising every other needle, and the other group comprising the needles alternating with such needles. Thus, 15 viewing Fig. 1, of the six wales of loops there presented, the wales 1, 1, 1 will be formed by needles of one set and the wales 2, 2, 2, will be formed by needles of the other set. It will be apparent that if the fabric be re- 20 garded as knitted from two sets of yarns one supplied to each set of needles, each loop of each wale from the yarn of one set includes a portion of the corresponding yarn of the other set that connects the two neighboring 25 loops formed from such other yarn and that the connecting portions of the loops form four sided and substantially diamond-shaped meshes upon the back of the fabric which thus exhibits upon one face thereof 30 parallel, longitudinal wales alternately of different yarns, and on the other face diamond-shaped meshes or reticulations formed by the connecting legs of the loops. Viewing Fig. 1, the loops are indicated at 3 and 35 the so-called diamond-shaped meshes or reticulated openings at 4. It will be apparent that while the principles of my invention are applicable to types of fabrics otherwise knitted they are particularly applicable to a 40 fabric of such open character as that herein shown but which is found wanting for summer use because of the minimized extent to which absorptive properties exist therein.

In order to knit such form of fabric as is 45 illustrated in Fig. 1, a machine such as shown in my Patent No. 810,578 may be employed, the yarn engaging hooks 16 being removed or rendered inoperative as previously stated and the yarn feeds being so arranged and 50 supplied respectively with the different grades of yarn, that in the operation of the machine yarns may be successively introduced to knit a fabric characterized as follows. That is to say, I preferably introduce 55 a tender, single-ply, soft, spun yarn, such as No. 40, to the two sets of needles, so as to knit what, for convenience of description, I term the courses of loops A, a, the loops A alternating with the loops a as will be readily 60 understood and being displaced therefrom vertically as clearly represented. I so feed the No. 40 yarn to the two sets of needles as to form preferably only a single complete course of loops upon all the needles, from such No. 65 40 yarn, and introduce at the proper period

and point to both sets of needles a somewhat heavier yarn, such as No. 28 cotton yarn, represented at B, b in said figure, and preferably knit a single complete course upon all the needles therewith, so that the loops of the No. 40 yarn are drawn through the loops of the No. 28 yarn. I in due course introduce upon both sets of needles at the proper period and point a still heavier grade of yarn as, for example, No. 16 cotton yarn, as represented at C, c, and knit preferably one complete course upon all the needles therefrom, so that the loops of the said yarn are drawn through the loops of the No. 28 yarn. I in due course introduce a heavy yarn, having the full absorptive properties desired, such, for example, as No. 10 cotton yarn, which may be knitted upon all the needles as represented at D, d in said figure, so that the loops thereof are drawn through the loops of the No. 16 yarn. Preferably, I form only a single complete course upon all the needles from such heavy yarn and suitably reintroduce No. 16 yarn, as represented at C, c, and then in succession reintroduce No. 28 and No. 40 yarn so as to form a single complete course from each of said yarns, as indicated at B, b and A, a respectively. In this manner the No. 40 cotton yarn is not subjected at once to the heavy strain of the No. 10 yarn but such latter yarn is introduced after such successive gradations as may be found desirable and after having introduced such heavy yarn of full absorptive property I preferably introduce the tender No. 40 yarn only after grading back to the same in the manner described.

In the remaining figures of the drawings I have indicated other forms of the invention. In Fig. 2, for example, I introduce upon all the needles a tender yarn, such as No. 40 cotton yarn, and as represented at E, e, following which in the manner already described I introduce such a yarn as No. 28 cotton yarn and as indicated at F, f. This, in turn, is succeeded by such a yarn as No. 16 cotton yarn and represented at G, g, to be in turn replaced by the heavy yarn, such as No. 10 cotton yarn, as indicated at H, h. Thus the heavy, fully absorptive yarn has been introduced after the desired gradations in the manner described in connection with Fig. 1. At this point, however, I may at once reintroduce the No. 40 yarn, as represented at E, e, in the succeeding course, following which are successively introduced No. 28 yarn, as indicated at F, f, No. 16 yarn, as represented at G, g, and the heavy No. 10 yarn, as represented at H, h. In this manner I do not draw the loops of the heavy No. 10 yarn directly through those of the tender No. 40 yarn, but may, under proper conditions, introduce the loops of such tender No. 40 yarn into the loops of the heavy No. 10 yarn. If very strong yarn be used, such, for

example as linen, which I find I may readily employ in knitting upon that type of machine disclosed in my said Patent No. 810,578, or two or three ply cotton yarn, I may directly introduce a heavy, fully absorptive yarn into the loops of a very much lighter yarn. Thus in Fig. 3 is represented a fabric which may, for example, be formed from lisle thread, and in which if desired two complete courses may be knitted from a fine yarn, as indicated at I, i, I, i, in said figure, following which yarn I introduce a heavy yarn at J, j, after which I introduce the fine yarn I, i, as represented for the desired number of courses. In such a fabric as that illustrated in Fig. 3 it will be apparent that the heavy annular ridge contrasts even more strongly with the intermediate portions of the fabric than is the case in Fig. 1, in which the said heavy ridge is approached and receded from by gradations.

As represented in Fig. 4, I may, in the case of very strong yarn such as above referred to, introduce a fine yarn upon all the needles as represented at K, k, K, k, and then, upon one set of needles, introduce a heavy, fully absorptive yarn as represented at L, and, upon the other set of needles, introduce an intermediate sized yarn, as represented at l, after which I may at once directly reintroduce the fine yarn K, k as represented. It will be apparent that not only in the form of the invention shown in Fig. 4 but also in that shown in each of the other figures of the drawings, I may introduce a yarn of one size or strength upon one of the sets of needles and a yarn of another size or strength upon the other set of needles to make a single complete course upon all the needles.

In Fig. 5 I have shown a fabric in which I preferably first introduce upon both sets of needles a tender yarn, such as represented at M, m, following preferably a single course of which I introduce a somewhat heavier yarn, as represented at N, n, upon all the needles and then introduce upon one or both sets of needles, and as herein shown upon both sets of needles, two sets of respectively parallel yarns, as represented at O, P, and o, p, one of which parallel yarns of each set may be a very heavy yarn and the other a light yarn, the combination of which it is apparent will supply an exceedingly heavy and fully absorptive yarn. Before introducing the yarns M, m, I may introduce exceedingly tender yarns I', l', which will be reintroduced at the proper point.

In Fig. 6 I have represented a fabric wherein I may first introduce a light but strong yarn, such as represented at Q, q, for the desired number of courses, following which I introduce upon one set of needles only a heavy yarn, such as represented at R, the needles of the other set still knitting with the fine yarn q, which may, after one course,

be reintroduced upon the needles of the first set as represented at Q.

It will be apparent that the references in the specification to cotton yarn and to particular sizes or strengths of cotton yarn are by way of example merely, and that I am in no wise limited thereby, inasmuch as any desired material may be employed, or, indeed, combinations of material in such desired sequence or variation as may be considered desirable and which would be within the scope of my invention. It will further be apparent that many combinations or variations of the fabrics represented herein may be effected.

Although I find it highly desirable to approach the introduction of a heavy yarn by successive gradations and to recede from such introduction in a similar manner, yet my invention is not limited thereto. Having particular reference to the open or reticulated type of fabric disclosed in Fig. 2 of my said Patent No. 865,279, I consider myself the first to recognize the desirability of introducing into the fabric a material that imparts that absorptive property largely lacking in a garment constructed such as that disclosed in the said figure when made throughout of a very light yarn.

Having thus described my invention, I desire it to be understood that although I have employed specific terms they are used in a generic and descriptive sense merely and not for purposes of limitation, the scope of the invention being set forth in the following claims.

1. A knitted fabric having one or more open courses of fine yarn and one or more close courses of heavy yarn, the said courses being of low and high absorptive powers respectively and separated in both directions longitudinally of the fabric by zones composed of complete courses of yarns of a plurality of grades of strength.

2. A fabric knit from two sets of yarns, all the knit loops of which appear in wales upon one face, loops of each yarn being drawn through loops of its kind only, a course or courses being formed from a fine yarn of each set of low absorptive power and a course or courses being formed from a heavy yarn of each set of high absorptive power, said course or courses of fine and heavy yarns respectively being separated in at least one direction lengthwise of the fabric by a course or courses of yarn from each set and of intermediate strength.

3. A fabric knit from two sets of yarns, all the knit loops of which appear in wales upon one face, loops of each yarn being drawn through loops of its kind only, a course or courses being formed from a fine yarn of each set of low absorptive power and a course or courses being formed from a heavy yarn of each set of high absorptive power.

power, said course or courses of fine and heavy yarns respectively being separated in both directions lengthwise of the fabric by a course or courses of yarn from each set and 5 of intermediate strength.

4. A fabric knit from two sets of yarns, all the knit loops of which appear in wales in one face, loops of each yarn being drawn through loops of its kind only, a course or 10 courses being formed from a fine yarn of each set of low absorptive power and a course or courses being formed from a heavy yarn of each set of high absorptive power, said course or courses of fine and heavy yarns

respectively being separated in both directions longitudinally of the fabric by a zone composed of yarns from both sets, there being a plurality of yarns in said zones of each set, said plurality of yarns of each set differing from each other in strength.

In testimony whereof, I have signed my name to this specification, in the presence of two subscribing witnesses.

BERNARD T. STEBER.
